UNITED STATES PATENT OFFICE.

HUGH CAMPBELL, OF ELLAND, COUNTY OF YORK, ENGLAND.

GAS-ENGINE.

SPECIFICATION forming part of Letters Patent No. 367,184, dated July 26, 1887.

Application filed February 28, 1887. Serial No. 229,071. (No model.) Patented in England June 9, 1885, No. 6,990.

To all whom it may concern:

Be it known that I, HUGH CAMPBELL, a subject of the Queen of Great Britain, residing in Elland, county of York, England, have invented 5 certain new and useful Improvements in Gas-Engines, of which the following is a specification.

This invention has reference to explosive gas-engines wherein in case the engine has but 10 a single piston and cylinder an explosion will occur at every complete reciprocation of the piston; but in case there is a double piston and a compound cylinder there will be two such explosions, whereby the working capacity of 15 the engine will be increased.

The invention consists in the general construction of engines of this class, in mechanism for controlling the speed of the engine, and in mechanism for igniting the charge.

20 The invention is illustrated in the accompanying drawings, wherein—

Figure 1 is a sectional elevation, and Fig. 2 a sectional plan, of an engine wherein there is a double cylinder and a double piston working 25 therein, ignition taking place at both ends of the cylinder. Fig. 3 is a sectional elevation, and Fig. 4 a sectional plan, of an engine having two cylinders side by side, the pistons of which are both connected to the same crank-30 shaft. Fig. 5 is a vertical cross-section of the engine shown in Figs. 3 and 4, through the exhaust-port, showing the mechanism for controlling the exhaust-valve. Figs. 6 and 7 are detail views of the ignition mechanism. Fig. 8 is 35 an end elevation, Fig. 9 a sectional elevation, Fig. 10 a sectional plan, and Fig. 11 a cross section, (on a plane indicated by the line *a b* in Fig. 10,) of a gas-engine having a single cylinder. Figs. 12 and 13 are diagrams illustrating the movements of the crank and piston, respectively, in an engine such as is shown in Figs. 8 to 11. Fig. 14 is a detail view on an enlarged scale of a modified mechanism for controlling the exhaust-valve; and 40 Fig. 15 is a detail view on an enlarged scale of mechanism for controlling the inlet-valve.

Referring to Figs. 1 and 2, D E represent the two ends of a long cylinder, in which is fitted a long trunk-piston, C. Said piston carries at its center a shaft, C', extending through 50 slots C² in the sides of the cylinder, the opposite ends of said shaft being connected by suit-

able rods to cranks B B on a drive-shaft, A. An ignition-chamber, d, is located at the end of each cylinder, each ignition-chamber being supplied with the combustible mixture through inlet check-valves J J. The cylinder is provided with two exhaust-ports, F F, for each end, each exhaust-port being controlled by a check-valve, M. The exhaust-port at each 55 end is located at a distance from the end of the cylinder equal to one-half of the travel of the piston.

The operation of the engine is as follows: Assume the piston to have just started toward 60 the crank-shaft, impelled by the explosion of the gases at the E end of the cylinder. The movement of the piston in this direction creates a partial vacuum, opening the check inlet-valve J, admitting gas and air behind 65 the spent gases and the products of combustion. This action continues after passing the exhaust-port (since the partial vacuum caused by the movement of the piston seats the valve M firmly) until the piston reaches its limit of 70 movement in this direction. When it has reached this limit, the E end of the cylinder is filled with spent gases in the part nearest the piston and with fresh gas at the ignition end. On the return movement of the piston it compresses the gases, and so closes the inlet-valve 75 J and opens the exhaust-valve M. Further movement of the piston expels the spent gases until the piston reaches and passes the exhaust-port F, when nothing remains in the E 80 end of the cylinder except the fresh gas. This fresh gas is then compressed by the piston until the piston reaches its limit of movement in this direction, when the explosion again 85 takes place, and the movements are repeated. In the meanwhile the same movements have 90 taken place in the D end of the cylinder, and need no additional description. Thus in an engine thus constructed there will be two explosions at each rotation of the shaft A.

In Figs. 3 and 4 is shown an engine wherein two single-acting cylinders are placed side by side, the two pistons B' C of which are arranged to be connected to oppositely-located cranks B on the same shaft A. In this case 100 the cycle of movements in each cylinder is exactly similar to that in either end of the cylinder shown in Figs. 1 and 2. The pistons in the two cylinders alternate in their move-

ments, and there are two explosions at each rotation of the shaft A.

The mechanism for controlling the speed of the engine by regulating the valve M in the exhaust-port, and which is applicable to either form of engine described, is illustrated in Fig. 5. The valve M is provided with a valve-rod, *a*, which at its upper end outside of the valve-casing is connected to one end of a lever, *b*, pivoted to any suitable support. The opposite end of the lever is connected to a governor, *L*. When the speed of the engine exceeds the prescribed limit, the governor-balls will be lifted, thus depressing the end of the lever *b*, connected thereto, and lifting the valve M from its seat. The exhaust-passage will thus be permanently open as long as the speed is too great. When the valve is open, fresh gas will no longer be introduced into the cylinder, since the vacuum caused by the movement of the piston will be broken, and hence the inlet-valve will not be opened to admit fresh gas. Therefore, no fresh gas being admitted, the speed of the engine will soon be reduced, lowering the governor-balls, and closing the valve M. As soon as the valve is closed, the normal operation of the engine will be resumed.

The mechanism for igniting the combustible gases is shown in Figs. 6 and 7, wherein is shown a bent pipe, *K*, which pipe is connected at its two ends to the ignition-chamber *d* of both cylinders when arranged side by side, as shown in Figs. 3 and 4. This pipe is so arranged that there is no through passage in it, communication between the two ends being prevented by a stop-piece or solid part, *c*, formed in the pipe. This compound pipe is heated by a single light or jet, which keeps it at a red heat, so that when the combustible mixture is alternately compressed into each branch of the pipe ignition will be produced in the cylinders at the proper time. In this manner only one light is required to cause the explosion in both cylinders.

In Figs. 8 to 11 is shown a single-cylinder engine having but a single piston. The main shaft A has accordingly but a single crank, B. This engine is shown more completely than those previously described. Air is admitted through a perforated plate, *G*, into a reservoir, *H*, and gas is admitted through the pipe *P*. The gas and air are conveyed by inlet *I*, closed by inlet check-valve *J*, to the ignition-chamber *d*. An ignition-pipe, *K*, similar to that shown in Figs. 6 and 7, but with only a single branch, connects with the ignition-chamber, and is heated by gas introduced through pipe *e*. The exhaust-port *F* is arranged at the side of the cylinder.

The action of the piston of this engine is illustrated by the diagrams Figs. 12 and 13, Fig. 12 showing by the circle *f* the different positions of the crank B and Fig. 13 the positions of the piston. When the crank is at points *g* and *j*, the piston is at line *g*, and when the crank is at positions *h* and *i* the piston is at line *h* and *i*. The action of the piston in reference to the

gases is exactly the same as that described in connection with the engine shown in Figs. 1 and 2. One single-acting cylinder alone being shown, only one explosion occurs at each rotation of the shaft A.

As the exhaust-port in this engine is at the side, a slightly-modified form of controlling mechanism for the exhaust-valve is required, which is shown in detail in Fig. 14. The valve M in this case opens downward, being held to its seat by a spiral spring, *l*, surrounding its stem *m*. The governor-balls in this case are arranged to lift the end of the lever *b*, connected thereto, and so depress the valve, thereby opening the same when the speed of the engine rises above the normal.

In addition to controlling the speed by the exhaust-valve, there may be used in connection therewith mechanism for controlling the admission of the gas, so as to prevent possible waste of the same. This mechanism is illustrated in Figs. 8, 10, and 15. The gas-inlet pipe *P* is controlled by a valve, *p*, which is normally seated by a coiled spring, *r*, bearing against a collar, *Q*, carried by the valve-stem. In this case a similar governor, *L*, with lever *b*, is employed; but instead of the lever being connected to the valve-stem, there is suspended from it a rod, *t*, carrying at its lower end a tap-piece, *s*. The rod *t* hangs immediately in line with the valve-stem. On the shaft A is a cam, *R*, around which is a clip, as is usual in these cases, which clip is connected to a rod, *S*, which at every revolution of the cam strikes gently the tap-piece *s*, thereby forcing in the valve-stem and opening the valve to admit the gas. In case, however, the speed of the engine becomes too great, the action of the governor lowers the rod *t*, so that the tap-piece *s* is no longer struck by the rod *S*. The valve *P* thus remains closed, shutting off the supply of gas until the lowered speed of the engine brings the tap-piece again in line with the rod *S*.

I claim as my invention—

1. In a gas-engine, a cylinder, a piston moving therein, and an ignition-chamber at one end of the cylinder, in combination with a gas and air inlet valve opening into said ignition-chamber, which valve is opened by the vacuum caused by the outward movement of the piston, an exhaust-port located in the cylinder at a point midway of the movement of the piston, and a valve in the exhaust-passage, which is opened by the compression of the gases caused by the inward movement of the piston, substantially as set forth.

2. In a gas-engine, an elongated cylinder, a piston moving therein, and ignition-chambers at both ends of said cylinder, in combination with gas and air inlet valves opening into said ignition-chambers, which valves are opened by the vacuum caused by the movement of the piston away therefrom, exhaust-ports at each end of the cylinder, each located at a point midway of the movement of one end of the piston, and valves in the exhaust-passages which are opened by the compression of the

gases caused by the movement of the piston toward the ignition ends of the cylinder, substantially as set forth, whereby when the piston is expelling the spent gases it is at the same time compressing the fresh gases for a new explosion.

3. In a gas-engine, a cylinder, a piston working therein, an ignition-chamber at one end of the cylinder, an air and gas inlet valve opening into the ignition-chamber, which is opened by the vacuum caused by the movement of the piston away therefrom, an exhaust-port in said cylinder at a point midway of the movement of said piston, and a valve in the exhaust-passage which is normally closed and is opened only by the compression of the gases caused by the return movement of the piston, in combination with a speed-governor, and connections between said governor and exhaust-valve, substantially as set forth, whereby when the speed of the engine exceeds the normal said exhaust-valve will be opened, thus destroying

the vacuum caused by the outward movement of the piston, so that the inlet-valve will remain closed.

4. In a gas-engine, two cylinders, ignition-chambers at the ends thereof, and pistons working in said cylinders which compress the fresh gases into said ignition-chambers, in combination with a bent tube or pipe opening at opposite ends into said ignition-chambers, and a stop-piece in said pipe which closes communication between the two ignition-chambers, substantially as set forth, whereby said bent pipe may be heated by a single jet and one jet will serve for the ignition of the gas in both cylinders.

In witness whereof I have hereunto signed my name in the presence of two subscribing witnesses.

HUGH CAMPBELL.
